PNEUMATIC KNITTING DEVICE

Marcel Vitoux, Troyes, France, assignor to American Vitos Company, Inc., New York, N. Y., a corporation of Delaware

Application August 6, 1947, Serial No. 766,697
In France December 10, 1942

Section 1, Public Law 690, August 8, 1946
Patent expires December 10, 1962

1 Claim. (Cl. 66—1.5)

1

This invention relates generally to knitting devices for repairing of runs or ravellings in knitted fabrics, particularly hosiery. The particular type of mending device to which the present invention relates, comprises a cylindrical holder which is connected to a source of power, such as compressed air to operate the needle and piston to which it is attached, the holder being held between the thumb and index finger by the operator during the reweaving operation.

One object of the invention is to increase the speed of operation of such mending devices from the present 1800-2000 mesh per minute, to a speed of 2500 to 3000 mesh per minute, even in very fine articles, such as silk stockings.

Another object is to produce a device of this nature which will reduce to a minimum the fatigue of the hand of the operator, and at the same time permit the article being knitted to be held less taut on its support, thereby not only reducing the chances of damaging the said article, but in addition, and above all, obtaining a better repair job.

A further object of the invention is to produce a device of this character of greatly reduced weight or mass, thereby eliminating to a great extent the vibrations which in the present day devices cause the hands of the operator to become fatigued.

Another object of the invention is to produce a device of the character described in which the maximum simplicity of construction and operation is secured.

Other objects and advantages will appear as the nature of the improvements is better understood, the invention consisting substantially in the novel arrangement and correlation of parts herein fully described, and illustrated in the accompanying drawings, wherein similar reference characters are used to denote corresponding parts throughout the several views, and then finally pointed out and specifically defined and indicated in the appended claim.

The disclosure made the basis of exemplifying the present inventive concept suggests a practical embodiment thereof, but the invention is not to be restricted to the exact details of this disclosure and the latter, therefore, is to be understood from an illustrative, rather than a restrictive, standpoint.

In carrying out the objects of the present invention it was found advantageous to provide a substantially light walled cylindrical casing having a hollow interior in which is mounted near its upper end a movable piston maintained

2

in upper position by a spring and provided with an opening for receiving the upper shank end of a needle guided in a slotted bushing at the bottom of the casing. The top of the casing is provided with a finger piece having an inlet end for connection with the tubing leading to the source of power, such as compressed air for operating the device.

The invention will appear more clearly from 10 the following detailed description when taken in connection with the accompanying drawings, in which—

Figure 1 is a side elevation of the improved device;

15 Figure 2 is a longitudinal sectional view taken on line 2—2 of Figure 1; and

Figure 3 is a cross sectional view taken on line 3—3 of Figure 2.

Referring now to the drawings in detail, the 20 numeral 5 indicates a cylinder or casing which is provided with a lower central bore, an upper bore 7 concentric with the bore 6 and of somewhat larger diameter to form a shoulder 8 at the juncture of said bores. The top of the casing 5 is provided with an enlargement 9 having an inner threaded counterbore 10 for the reception of 25 a plug 11 having disks 12 which serve as finger pieces for holding the device. The said plug 11 is provided with bore 13 and nipple 14 for the reception of a tube 15 leading to the source of compressed air not shown.

30 Located within the bore 7 is a coiled compression spring 16 which rests upon the shoulder 8 formed by the bores 6 and 7. The said spring 35 supports at its upper end a piston 17 which comprises a leather cup 18 clamped between an upper disk 19 and a lower washer 20, the upper disk 19 having a centrally drilled hub 21 into which extends the upper end of a knitting needle 22 and held in place in said hub by means of a set screw 40 23. The washer 20 may be locked in place by any suitable means, as for instance a pin 24 extending partly into the hub 21. A shock absorbing spring 25 is interposed between the bottom 45 of the plug 11 and the top of the disk 19. The needle 22 may be of the sliding catch type or as shown of the type having a small blade 26 pivoted at the working end thereof.

The piston and needle are moved downwardly 50 by the action of the compressed air against the leather cup 18 and disk 19 and returned by the return spring 16, the needle passing through a two sectional bushing 27 having a rectangular slot 28 which conforms to the cross section of 55 the needle. Thus the needle which forms an ex-

tension or shank of the piston, due to its passage through the rectangular slot or opening 28 guides and holds the entire movable operating device in proper position.

It will therefore be seen from the above that due to the extreme lightness of the construction of the reweaving device a great amount of the usual vibrations of such devices is eliminated, with the consequent result that there is a substantial decrease in fatigue of the operator's hand and a corresponding increase in the speed of operation of the device, and a better finished job.

It is apparent that the specific embodiment shown above has been given by way of illustration and not by way of limitation, and that the structure above described is subject to wide variation and modification without departing from the scope or intent of the invention, all of which variations and modifications are to be included within the scope of the present invention.

What is claimed is:

A knitting device comprising a cylinder having a longitudinal bore, a piston at the upper end of said bore slidably arranged therein, a spring upon which said piston is supported, a bushing at the

lower end of the cylinder, having an opening formed therein, and a knitting needle carried by the piston and passing through the opening in the bushing, the contour of said opening and cross-section of the needle corresponding one to the other and being such as to prevent rotary movement of the needle, said piston including a leather cup and means connected with said leather cup for supporting an end of said knitting needle directly below said leather cup.
